UNITED STATES PATENT OFFICE.

LEIGH S. BACHE, OF MIDDLESEX BOROUGH, NEW JERSEY, ASSIGNOR TO BOUND BROOK OIL-LESS BEARING COMPANY, OF BOUND BROOK, NEW JERSEY, A CORPORATION OF NEW JERSEY.

TOP-ROLL SADDLE AND STIRRUP.

1,276,707.

Specification of Letters Patent. Patented Aug. 27, 1918.

Application filed September 22, 1915. Serial No. 52,093.

To all whom it may concern:

Be it known that I, LEIGH S. BACHE, a citizen of the United States, and a resident of the borough of Middlesex, in the 5 county of Middlesex and State of New Jersey, have invented certain new and useful Improvements in Top-Roll Saddles and Stirrups, of which the following is a full, clear, and exact description, whereby any 10 one skilled in the art may make and use the same.

The invention relates to spinning frames and is particularly directed to certain new and useful improvements in adjustments 15 for top roll saddles such as are employed upon the rolls of spinning frames.

The object of the present invention is to provide a ready adjustment for the stirrup and weight with reference to the saddle 20 member, and of course, incidentally with reference to the rolls upon which the saddle member bears. In its object, it is adapted to provide a ready adjustment by which the tension upon the top saddle member and 25 the underlying rolls may be effected during the operation of the machine and without any special tools or apparatus, other than that provided directly upon the saddle members.

30 A further object is to provide a very simple form of adjustment for the stirrup and weight by which the stirrup may be manipulated by the hands of the operator without special tools and which will hold its 35 position after adjustment.

Referring to the drawings:

Figure 1 is a side elevation of the saddle with the top rolls diagrammatically 40 illustrated as they appear for spinning short-fibered staple.

Fig. 2 is a perspective view of the top saddle member illustrating the adjusting plate.

Fig. 3 is a perspective view of the adjusting plate removed from the saddle member.

Fig. 4 is a perspective view of the adjusting plate and top saddle member illustrating a possibility of using a special tool for securing adjustments.

50 Fig. 5 illustrates a slightly modified form of adjusting plate and the appurtenant parts.

Fig. 6 is a fragmentary view illustrating the knife-edge adjusting effects.

It is not at all a new idea to provide an 55 adjustment on a saddle block for the stirrup or weight strap. Many devices of a more or less complicated character have been devised and used in conjunction with top-saddle members.

60 Where metallic saddles employing a lubricant are used, it has been a common practice to arrange a member bearing the stirrup and adjustable along the upper surface of the top-saddle member. Adjustable 65 plates bearing the stirrup have been used, and adjusting screws have been employed. It has also been a practice to form notches in the upper surface of the top-saddle member so that the stirrup or weight might 70 be moved into one or the other of the notches.

The present invention relates to a special type of saddle block. The block herein described is formed from impregnated 75 wood or fiber and is self-lubricating. That is, it requires no oil or grease other than that which is an inherent part of its composition.

Where lubricating fiber is used for the 80 saddle members, the lubrication is uniform throughout the entire body of the structure, and where an attempt is made to form grooves, notches or similar adjusting points for the stirrup there is great liability of 85 the stirrup slipping. The grooves or notches cannot be accurately and sharply defined, and with the vibration and a considerable weight hanging upon the stirrup, it has been found that the stirrup slips 90 from one notch to another.

The present invention relates to an effective means for preventing slippage, and obviates the necessity of weakening the saddle member by forming grooves or notches of 95 sufficient depth to hold the stirrup. It also provides for an easy and ready adjustment of the stirrup along the saddle member without stopping the machine and without requiring special tools.

100 The top rolls of spinning machines of necessity must be adjusted closer to or farther from the front or delivery roll in order to adapt them to the varying condition of the roving or sliver. It is usually desirable 105 to vary the pressure exerted on the several top rolls through an adjustment of the weight strap or stirrup. The weight must

be distributed to exert certain pressures upon the rear roll and intermediate roll and upon the front roll.

It is also very desirable to provide an adjustment, by which the stirrup or support to which the weight is attached may be positioned along the saddle member, to vary the pressure upon the rolls, with considerable nicety, even while the machine is in operation.

Obviously it is quite as essential to have the adjustment readily under the hand of the operative, so that, no special tool such as screw drivers or the like are necessary for securing adjustment. Ordinarily there is a considerable weight hanging upon the stirrup and if this weight must be raised, considerable exertion is necessary or a special tool must be employed for raising the weight or for readily shifting the stirrup.

Where metallic saddles are employed, screws and other fixtures may be readily applied for securing adjustments.

The present device provides efficient adjustments in conjunction with a fibrous self-oiling block and gives sufficient gradation of adjustment to be thoroughly effective.

Referring to the drawings *a*, indicates the front roll, *b*, intermediate roll and *c*, the rear top roll.

These rolls coöperate with corresponding lower rolls *a'* *b'* *c'*.

As illustrated in the drawings a two part saddle is shown. This consists of an upper saddle member 1, and a lower saddle member 2. The former bears upon the front top roll and upon the lower saddle member 2. The lower saddle member bears upon intermediate roll *b*, and the rear roll *c*, the upper and lower saddle members are by preference formed with interengaging parts. The lower member 2 has formed in its upper surface a slot or groove 3, into which projects the fin 4 which permits longitudinal adjustment of the saddle parts while preventing lateral displacements or separation thereof.

The saddle parts are of a male and female type in their engagements.

Mounted upon the upper saddle 1, there is an adjusting plate 5, which has peculiarly formed serrations 6, extending transversely thereof and in parallel lines.

This plate is preferably provided with dependent side members or lugs 7, with tangs or clips 8, which may be conveniently driven into the fiber of the material to firmly hold the plate in place.

The stirrup is of the usual form as illustrated at 9, and is perforated as at 10 to slip over the upper saddle member. The under edge of the perforation 10 as illustrated at 11 engages the serrations of the plate.

If desired the engaging portions of the stirrup may be sharpened or beveled so that

there is practically a knife-edge engagement of the stirrup with the serrated plate.

The effect of such an arrangement is illustrated in Fig. 6 on enlarged scale.

Referring to this figure, it will be noted that the sharpened knife-edge 12 of the stirrup bears as at 12^a upon the beveled portion of one of the serrations. Due to the pull of the weight, its tendency is to crowd down into the lower portion 13 of said serration. As the pull of the weight occurs upon the stirrup, the sharp edge 14 of the serration bears against the face of the stirrup. Thus during any vibration, there are two knife-edge points 12 and 14 for the stirrup, 80 and therefore there is a very delicate form of self-adjustment.

It will be noted that the serrations are sharply and definitely formed in juxtaposition to each other, and that they are so formed that there is a slight well defined cam surface over which the stirrup may be moved from one serration to another.

As illustrated in Fig. 1 to Fig. 4 of the drawings, the declination of the serrations is all in one direction. It is therefore quite obvious that, starting with the stirrup in its lowermost position adjacent to the front roll *a*, it is a simple matter to place the thumb against the stirrup and force it along the cam surface of the serrations until a perfect adjustment is effected.

In Fig. 5 its serrations are shown with an equal pitch on both sides so that the stirrup may be moved from one end to the other over equally disposed cam surfaces.

In Fig. 4, a convenient means is illustrated for using a tool if desired. In this case an opening 15, is provided centrally of the stirrup and a screw driver or small bar 16, may be inserted in the opening 15, to pry up the stirrup and slip it from one serration to another. Such device is of course entirely unnecessary in adjusting from the front roll *a*, which is the normal starting position, toward the intermediate roll *b*. This arrangement is merely illustrated to show the possibilities of moving the stirrup without directly placing the hand upon the saddle member and other parts.

Obviously the exact form of the plate might be varied to suit the exigencies of any particular type of stirrup in common use.

Ordinarily the most common type is a serrated one, such as is illustrated. It is also apparent that means for fastening the plate to the top saddle might be modified and varied, although the type illustrated has special advantages inasmuch as, the tangs 8, prevent longitudinal displacement, while the downwardly-turned edges or lugs 7, prevent lateral displacement. The plates may be made of very thin light metal and inasmuch as no perforation is necessary in the saddle block for securing them, its strength and its

uniform character for heat radiation is not impaired.

What I claim as my invention and desire to secure by Letters Patent is:

- 5 1. In a saddle block for top rolls, a saddle member, a weight stirrup for said member, and an adjusting plate upon which the stirrup rests, said plate having a series of cam surfaces forming inclines arranged transversely of the plate and upon which inclines the stirrup rests and over the upper edges of which cams the stirrup may be pushed.
- 10 2. In a saddle block for top rolls, a saddle member, a weight stirrup for said member having a "knife-edge" for its line of engagement with an adjusting plate and an adjusting plate upon which the "knife-edge" of the stirrup rests, said plate secured to the saddle member and having sharply defined transverse cam surfaces arranged in series transversely of the plate and all undercut in the same direction and providing cam surfaces upon which the "knife-edge" of the stirrup rests with the upper edge of the adjacent serration impinging against the face of the stirrup.
- 15 3. A saddle block, having an adjusting plate for a weight strap or stirrup, said plate having sharply defined transverse serrations forming oblique cam surfaces arranged in parallelism transversely of and from end to end of the plate, and integral tangs for securing the plate upon the saddle

member to prevent lateral or sidewise movement thereof. 35

4. A saddle block, having an adjusting plate for a weight strap or stirrup, said plate having sharply defined transverse serrations forming oblique cam surfaces all undercut in the same direction and arranged in parallelism transversely of and from end to end of the plate, down turned tangs adapted to be pressed into the upper surface of the saddle block to secure the plate, 40 and lugs, embracing the sides of the saddle member to prevent lateral displacement. 45

5. An adjusting device for saddle blocks consisting of a top saddle member having a plate provided with sharply defined transverse serrations forming cam surfaces upon which surfaces the weight strap may rest and may move, a perforated weight strap resting upon said plate between its serrations and with its edge bearing upon one of the cam surfaces, and having an opening extending above its edge of contact with the plate, said perforation providing an opening through which a lifting bar may be inserted, and in conjunction with the serrated plate forming a means by which a lifting bar may be used as a lever for moving the stirrup into engagement with either of the cam surfaces. 50 55 60
